UNITED STATES PATENT OFFICE.

WILLIAM L. HARDWICKE, OF RICHMOND, VIRGINIA, ASSIGNOR OF ONE-HALF TO GEORGE W. WYNANT, OF RICHMOND, VIRGINIA.

STATIC DISCHARGER.

No. 836,576.

Specification of Letters Patent.

Patented Nov. 20, 1906.

Application filed April 3, 1905. Serial No. 263,588.

To all whom it may concern:

Be it known that I, WILLIAM L. HARDWICKE, a citizen of the United States, residing at Richmond, in the county of Henrico and State of Virginia, have invented new and useful Improvements in Static Dischargers, of which the following is a specification.

The invention relates to an improved static discharger primarily designed for attachment to printing or other presses and operative to relieve the printed sheets of the charge of static electricity induced therein when subjected to the printing operation.

As is well known, the sheets of paper in passing through the printing-press develop a static charge of electricity, with the result that in the delivery of said sheets they adhere or stick together, producing an irregular delivery.

The main object of the present invention is to provide means for relieving the sheets of their static charge during the delivery of said sheets, whereby said delivery is effectively and properly maintained.

The preferred embodiment of the details of structure of my present invention will be described in the following specification, reference being had to the accompanying drawings, in which—

Figure 1 is a longitudinal sectional view illustrating my improved discharger connected with the delivery mechanism of a printing-press. Fig. 2 is a perspective view of the discharger. Fig. 3 is a rear elevation of the same. Fig. 4 is a broken perspective of the supporting-plate of the discharger.

The form of the invention as illustrated and described is to be applied to the cross-bar 1 of the longitudinally-movable carriage arranged above the delivery-tapes 2.

The discharger comprises a supporting-plate 3, preferably metallic and of the desired length and width. The plate is formed with a series of transversely-arranged parallel grooves or recesses 4, in which are removably inserted the discharge-needles 5, which are of such length as to project below the plate 3. A clamp-plate 6 is arranged to contact with the supporting-plate 3, overlying the needles and being secured in position by screws 7. The clamp-plate operates to secure the needles in their respective grooves, so as to maintain the lower or pointed ends of said needles in horizontal alinement.

A clamp 8 is secured at the respective ends 55 of the discharger, comprising a U-shaped strip within which the terminals of the connected supporting and clamp plates are secured by screws 9, the open end of the clamp projecting beyond said plates to receive the 60 transverse bar 1 of the delivery-carriage of the printing-press, set-screws 10, carried by the clamps, serving to secure them in position.

11 represents a guard-plate adjustably secured to the front side of the supporting-plate 3 through the medium of screws 12, engaging elongated slots 13 formed in said guard-plate. The guard-plate projects below the lower edge of the supporting-plate and is effective in preventing injury to the 70 operator by the needles in the event manual operation of the sheets is necessary during delivery.

The needles 5, of which there may be any desired number, are electrically connected 75 through the medium of a wire 14 of high conductivity, such as copper, which is terminally connected to one of the end needles and projected toward the other, being coiled around each needle in succession, as clearly 80 shown in Fig. 2. When in position on the press, the free terminal of said conductor is to be grounded through connection with any fixed part of the press.

In use, it being understood that the points 85 or lower terminals of the needles are so positioned as to just escape contact with the delivered sheet 15, the static charge of said sheet will be taken up by the needles and through the conductor 14 will be grounded. 90

It is understood, of course, that in the use of the invention as illustrated the delivery-tapes carrying the printed sheet are moving in one direction with said sheet, while the carriage carrying my improved discharger is 95 moving in the opposite direction, so that the needle-points are carried lengthwise above the sheet and effectively relieve said sheets of the static charge induced in the printing operation. 100

While I have shown and described my discharger as particularly adapted for use in conjunction with the delivery mechanism of printing-presses, it is obvious that it is equally applicable to other paper-handling machinery in which the paper is subjected to the induction of a static charge of electricity. 105

Having thus described the invention, what is claimed as new is—

1. In combination with the delivery mechanism of a printing-press including the delivery-tapes, of a static discharger connected with the mechanism and movable above and in reverse direction to the travel of the paper while the latter is on the tapes.
2. The combination with the delivery mechanism of a printing-press, of means connected therewith for relieving the sheets carried by said mechanism of the static charge of electricity, said means operating above the supported sheets in a direction reverse to the delivery movement of said sheets.

3. A static discharger comprising a supporting-plate formed with a plurality of grooves, needles seated in said grooves, a clamp-plate secured to the supporting-plate and overlying the needles, clamps secured at the opposite ends of the supporting-plate, a conductor joining the needles, and a guard-plate adjustably connected to the supporting-plate.

In testimony whereof I affix my signature in presence of two witnesses.

WILLIAM L. HARDWICK.
